UNITED STATES PATENT OFFICE.

JOSEPH B. ST. HELENS, OF ROCHESTER, NEW YORK.

METALLIC BOX.

1,065,404.

Specification of Letters Patent. Patented June 24, 1913.

Application filed May 2, 1912. Serial No. 694,614.

To all whom it may concern:

Be it known that I, JOSEPH B. St. HELENS, a citizen of the United States, and a resident of Rochester, in the county of 5 Monroe and State of New York, have invented a new and Improved Metallic Box, of which the following is a specification.

This invention relates to metallic boxes and is a continuation in part of applicant's 10 application, serially numbered 542,524, filed February 7, 1910.

The object is to provide a metallic box, and a blank therefor, that may be shipped and stored with the blank from which the 15 box is formed in its flattened out condition and from which the box may be readily formed by bending up the blank, to form the sides and ends of the box, along suitably creased lines. The side and end members 20 of the box have interlocking flaps adapted to be readily folded to locking position to rigidly hold and secure the sides and ends of the completely formed box in their normal positions without the aid of 25 solder or rivets or any fastening means other than such as is formed by the inter-engaging and inter-locking sides and end members themselves.

The accompanying drawings illustrating 30 a box in accordance with my invention are as follows:

Figure 1 is a plan view of the blank from which the body of the box is made. Fig. 2 is a plan view of the blank from which the 35 cover is made. Figs. 3, 4 and 5 are plan, side and end views respectively of the body of the box completely formed. Fig. 6 is a side view and Fig. 7 an end view of the cover completely formed. Fig. 8 is an enlarged transverse sectional view of the box 40 taken along the line $x-y$ of Fig. 4, but with the cover thereon, while Fig. 9 is a longitudinal sectional view of a part of the box taken along the line x^1-y^1 of Fig. 5.

Referring to the drawings, similar parts 45 are designated by similar letters of reference throughout the several figures of the drawings.

The body of a box in accordance with my 50 invention is formed from a blank, such as seen in plan view in Fig. 1, having a bottom member B bounded on each of its four sides with a crease, as indicated at v, and on the outer sides of the longer creases are 55 seen side members A, each having a finer

crease extending longitudinally thereof indicated at the dotted lines 1 and 4 and also having at each end thereof a similar and transversely extending crease, indicated at the dotted lines 6 and 7. Beyond the finer creases 1 and 4 are seen portions a adapted, when bent down as indicated in Figs. 3, 4, 5, 8 and 9, to form cover engaging and holding flaps or extensions. At the ends of each of these side members A there are seen 60 triangularly shaped flaps F adapted to be bent up at right angles with the sides A. These locking flaps F have locking ears f thereon. Along the line of the finer creases 1 and 4 in the sides A are seen slits s adapted to receive the locking flaps d later to be described. The ends of the box E have fine creases therein, as indicated at the dotted lines 5 and 8, beyond which are seen the flaps e while along the line of the 65 creases 5 and 8 are formed slits u adapted to receive the locking ears f. At the ends of each of the end members E, and beyond the fine creases indicated by dotted lines 2 and 3, are seen locking flaps D each carrying a locking ear d adapted to engage 70 through the slits s in the side members A.

In forming a box from such a blank the members A and E are bent up to form the sides and ends of the box with the flaps, 75 carried by one of such pair of opposite members, engaging within the inside of the box and with the flaps, carried by the other pair of such oppositely disposed members, engaging 80 outside of the box—in the drawings I have shown the flaps D as engaging outside 85 of the sides A and the flaps F as engaging inside of the ends E. Before bending up the sides and ends, as just above described, it is preferable to bend the locking ears f outwardly and away from the observer, with 90 reference to Fig. 1, along the dotted lines indicated where they unite with the flaps F while the ears d on the flaps D, are similarly 95 bent toward the observer. As the box is formed from the blank the ears f are inserted 100 so as to extend outwardly through the slits u while the ears d are inserted so as to extend inwardly through the slits s; after 105 which the ears f and d are bent downwardly against the ends and sides of the box, as indicated in Figs. 3, 4, 5, 8 and 9. The flaps e on the ends E may be bent downwardly on the inside of the box and against the ends F as indicated, while the flaps a are bent down 110

outside of the box in such a way as to be spaced from the sides A to comprise engaging and holding means for the slidable cover.

The cover is formed from a blank, such as seen in plan view in Fig. 2 and comprises 5 the main central portion C, bounded by suitable crease lines v^1 , and having side flaps c^1 adapted to be folded inwardly along the fine crease lines, indicated at the dotted lines 9 and 10, and within but spaced from the 10 flaps c , as clearly indicated in Fig. 8, so as to receive the cover holding flaps a between the parts c and c^1 . The cover is provided with end flaps P adapted to be folded down 15 along the heavy creases v^1 to form the ends of the cover and each of these end flaps P in turn is provided with an extension member p adapted to be formed around a suitable rod or core r , as indicated in Fig. 6, and 20 one of the end flaps as indicated in this figure may be folded downwardly to final position while the other one, as seen at the left in Fig. 6, may remain in its straightened out position until after being inserted over the box after which, when desired, it may 25 be bent down in the same way as the one seen at the right hand end of the cover in Fig. 6. To facilitate the locating of the core or rod r and the forming of the roll around the same the flaps P may have fine creases 30 formed therein as indicated at the dotted lines 11 and 12.

From the foregoing description of my box and the blank from which the same is 35 formed it is believed that the coöperation of the several parts thereof is sufficiently clear to call for no further explanation herein.

What I claim is:

1. A metallic blank for a box comprising 40 a centrally disposed bottom member having side members extending outwardly therefrom; one of the adjacent ends of adjacent side members carrying an end flap adapted, when said adjacent side members are bent to 45 position to form sides of the box, to be bent to lie against and in a plane parallel with the other side member and having its upper edge extended in a line comprising the upper edge of the box and substantially coincident 50 with the upper edge of the side of the box formed by the other side member and said other side member having a longitudinally extending side flap adapted to be bent down over said first named flap whereby said first 55 named flap operates, by engagement in the line of the fold between the second named side member and the longitudinally extending side flap thereon when folded down over the first named flap, to hold the first named 60 side member against outward movement independently of any frictional engagement of such first named flap against and between the second named side member and the longitudinally extending side flap folded 65 down therefrom, said second named side

member having a slit therein approximately at the fold between the same and the longitudinally extending side flap thereon and the end flap on said first named side member carrying an ear or lug adapted to engage through said slit and be folded down against the other side member. 70

2. A metallic blank for a box comprising a centrally disposed bottom member having side members extending outwardly therefrom; each of the adjacent ends of adjacent side members carrying end flaps adapted when said adjacent side members are bent to position to form sides of the box to be bent to lie against and parallel with the other side member and having its upper edge extended in a line comprising the upper edge of the box and substantially coincident with the upper edge of the side of the box formed by the other side member, each of said side 80 members having also a longitudinally extending side flap adapted to be bent down over the first named flap on the other side member whereby each of said first named flaps operates, by engagement in the line of the fold between the other side member and the longitudinally extending side flap thereon when folded down over the first named flap, to hold the corresponding side member carrying the same against outward movement independently of any frictional engagement of such first named flaps against 85 and between the side members and the longitudinally extending side flaps folded down therefrom, each of said adjacent side members having a slit therein approximately at the line of the fold between the same and the longitudinally extending flap thereon and the end flaps on each of said side members each carrying an ear adapted to engage 90 through the slit on the other side member and be folded down against the other side member, said end flaps on each of the side members adapted to be folded each one of them against the other side member, one on 95 the outside and the other on the inside of the box. 100

3. A metallic blank for a box having a bottom carrying side members, with one side member of each pair of adjacent ones thereof carrying a flap adapted to lie in a plane parallel and adjacent to the plane of the other one of such adjacent side members and with an ear or lug carried by such other side member of the pair adapted to be bent down 115 over the upper and free edge of the flap carried by the first named one of such adjacent side members, for holding the parts in proper relation, two opposite and parallel ones of the side members each carrying at its 120 upper and free edge, a longitudinally extending flap member adapted to be formed to coöperatively and slidably engage with members carried by a cover for holding the same in place. 125

4. A metallic box formed from a blank comprising a centrally disposed bottom member having side members extending outwardly therefrom; one of the adjacent ends 5 of adjacent side members carrying an end flap folded to lie against and in a plane parallel with the other side member and having its upper edge extended in a line comprising the upper edge of the box and substantially 10 coincident with the upper edge of the side of the box formed by the other side member and said other side member having a longitudinally extending side flap bent down over said first named flap whereby said first 15 named flap operates, by engagement in the line of the fold between the second named side member and the longitudinally extending side flap thereon when folded down over the first named flap, to hold the first named 20 side member carrying the same against outward movement independently of any frictional engagement of such first named flap against and between the second named side member and the longitudinally extending 25 side flap folded down therefrom, said second named side member having a slit therein approximately at the fold between the same and the longitudinally extending side flap thereon and the end flap on the first named 30 side member carrying an ear or lug engaging through said slit and folded down against the other side member.
5. A metallic box formed from a blank comprising a centrally disposed bottom 35 member having side members extending outwardly therefrom; each of the adjacent ends of adjacent side members carrying end flaps bent to lie against and parallel with the other side member and having its upper 40 edge extended in a line comprising the upper edge of the box and substantially coincident with the upper edge of the side of the box formed by the other side member each of said side members having also a longitudinally 45 extending side flap bent down over the first named flap on the other side member whereby each of said first named flaps operates,
- by engagement in the line of the fold between the other side member and the longitudinally extending side flap thereon when 50 folded down over the first named flap, to hold the corresponding side member carrying the same against outward movement independently of any frictional engagement of such first named flaps against and between 55 the side members and the longitudinally extending side flaps folded down therefrom, each of said adjacent side members having a slit therein approximately at the line of the fold between the same and the longitudinally 60 extending flap thereon and the end flaps on each of said side members each carrying an ear engaging through the slit on the other side member and folded down against the other side member said end flaps 65 on each of the side members folded each one of them against the other side member, one on the outside and the other on the inside of the box.
6. A metallic box formed from a blank 70 having a bottom carrying side members with one side member of each pair of adjacent ones thereof carrying a flap bent to lie in a plane parallel and adjacent to the plane of the other one of such adjacent side members 75 and with an ear or lug carried by such other side member of the pair bent down over the upper and free edge of the flap, carried by the first named one of such adjacent side members, for holding the parts in proper relation, two opposite and parallel ones of the side members each carrying at its upper and free edge, a longitudinally extending flap member formed to coöperatively and slidably engage with members carried by a cover 80 for holding the same in place and a cover having on its corresponding opposite edges members adapted to be thus coöperatively 85 engaged by such last named flap members.
